UNITED STATES PATENT OFFICE

114,636

DESIGN FOR AN ADVERTISING DOOR PULL

Ernest R. Erickson, Des Moines, Iowa, assignor to
C. E. Erickson Company, Incorporated, Des Moines, Iowa, a corporation of Iowa

Application February 20, 1939, Serial No. 83,108

Term of patent 7 years

To all whom it may concern:

Be it known that I, Ernest R. Erickson, a citizen of the United States, and a resident of Des Moines, in the county of Polk and State of Iowa, have invented a new, original, and ornamental Design for an Advertising Door Pull, of which the following is a specification, reference being had to the accompanying drawing, forming part thereof.

The matter shown in dotted lines is merely illustrative.

I claim:

The ornamental design for an advertising door pull, substantially as shown and described.

ERNEST R. ERICKSON.
